PROCESS AND APPARATUS FOR THREADING UP CONTINUOUS SPINNING MACHINES

Anne van der Mei, Arnhem, Netherlands, assignor to American Enka Corporation, Enka, N. C., a corporation of Delaware

Application November 14, 1946, Serial No. 709,750
In Germany May 26, 1941

Section 1, Public Law 690, August 8, 1946
Patent expires May 26, 1961

6 Claims. (Cl. 8—151.2)

1

This invention relates to the continuous spinning of viscose yarn and is more particularly concerned with a method and apparatus for the simultaneous and continuous after-treatment of a plurality of rayon yarns moving between a point of extrusion and a point of collection.

In the type of continuous spinning to which this invention relates, a plurality of freshly formed yarns are led from a spinning bath and are guided in parallel relationship by means of grooved rollers through a plurality of baths in which the yarns are contacted with various after-treating liquids such as washing water and desulphurizing agents. This type of spinning has the inherent advantage that a single after-treating bath may serve a large number of spinning positions, the yarns being led in parallel relationship over guide rollers into and through the after-treating liquid. However, in any spinning operation there is occasionally a yarn rupture, and where a number of yarns are running in a single bath a yarn failure is particularly serious since the broken yarn must be retrieved from the after-treating bath in which breakage occurred in such a manner as to avoid tangling and interference with the other yarns that are still running in that bath.

It is an object of the present invention, therefore, to provide a method and apparatus for the threading-up of a single thread or yarn in a continuous spinning machine of the type described above, which method and apparatus are characterized by efficient manipulation of the broken yarn without interference with other yarns running in parallel relationship in the same after-treating bath.

Other objects and advantages of this invention will be apparent upon consideration of the following detailed description of a preferred embodiment thereof in conjunction with the annexed drawings, wherein:

Figure 1 is a schematic view in side elevation illustrating the first stage of a threading-up operation conducted in accordance with the method of the present invention and involving employment of the apparatus thereof;

Figure 2 is a view similar to Figure 1 but illustrating the second stage in a threading-up operation;

Figure 3 is also similar to Figure 1 and serves to illustrate the third step in a threading-up operation; and

Figure 4 is a view similar to Figure 1 illustrating the fourth or final step in the threading-up operation.

Referring now to Figure 1 in greater detail, a number of threads issuing from a number of spinnerettes, not shown, are led in parallel re-

2

lationship over driven roller 10. From this point the threads are led downwardly into an after-treating bath 11 disposed in a container 12 and are guided through this bath by freely rotatable 5 grooved rollers 13 and 14. From the roller 14 the parallel threads are withdrawn by a driven draw-off roller 15 disposed at the right-hand end of the bath 11, as viewed in Figure 1. From the roller 15 the threads are propelled into a bath 16 within a container 17 and are led around a grooved roller 18 disposed below the surface of the bath 16. This procedure is continued through a number of baths constituting the full after-treating series required for any particular yarn. 10 In view of the fact that all of the figures of drawing are views in and elevation, the path defined by the plurality of parallel threads appears as a single thread, and is indicated by the reference numeral 19. The apparatus thus far described is entirely conventional. It will be noted, however, that the freely rotatable rollers 13, 14 and 18 are not mounted by conventional means within the respective baths, but are supported on one end of the arms of bell cranks 20, 21 and 22 15 respectively. The other arm of each of the bell cranks supports another freely rotatable grooved roller, rollers 23, 24, and 25, corresponding in structure and functions to the rollers 13, 14 and 18, also being supported by bell cranks 20, 21 and 22 respectively. Additionally there are provided driven rollers 26 and 27 located at the left-hand edge of each bath. By mounting the freely rotatable rollers in pairs on bell cranks and by providing driven rollers such as 26 and 27, an 20 arrangement is provided whereby it is possible conveniently to thread-up the machine after breakage of an individual yarn. Let it be assumed that one of the yarns 19, which will be hereinafter referred to as yarn 19a, breaks during 25 the passage through the container 12. When this condition occurs the operator immediately pulls the yarn 19a from the bath 11 and leads it under the roller 23 and around the roller 26. The roller 26 is driven at a takeup speed corresponding to 30 the spinning speed so that a loose running end is immediately avoided. After looping the yarn 19a around the roller 23 and when succeeding portions of that yarn are being taken up on roller 26 the operator turns the bell crank 20 in a counterclockwise direction, as viewed in Figure 1, causing the roller 23 to assume the position formerly occupied by the roller 13. This causes the yarn 19a to 35 assume the same position in the left-hand end of the bath as the other yarns which are running parallel to it, see Figure 2. At this point the operator pulls a loop of yarn 19a between the roller 23 and the driven roller 26 and passes this 40 loop over roller 24 to bell crank 21, as may be 45 50 55

seen in Figure 3. Thereafter, the bell crank 21 is turned in a counterclockwise direction until the roller 24 assumes the position formerly occupied by the roller 14, see Figure 4. At this time the yarn 19a is separated from the driven roller 26, 5 passed over the driven roller 15, under roller 25 and wound around driven roller 27. From this point on, the threading-up of the machine through the bath 16 and any succeeding baths, is effected in the manner previously described. After 10 threading-up has been completed, the bell cranks 20 and 21 may be restored to their original position by simply rotating them in a clockwise direction. This movement, as will be apparent 15 from a study of the drawings, will not affect the thread path through the various treatment baths and can be effected at any time during the running of the threads.

While the foregoing description has been concerned with but one form of the invention, it is apparent that various modifications are contemplated within the scope of the appended claims. For example, the pairs of unitary grooved rollers may be disassembled into individual rollers, each having an individual groove for guiding a thread through the bath.

What is claimed is:

1. In continuous spinning apparatus including a liquid bath, means for feeding yarn to said bath, and means for withdrawing yarn from said bath, the improvement that comprises a plurality of spaced yarn guiding elements, means for supporting said elements for successive movement into a yarn guiding position within the bath and an idle position above the bath and driven yarn storage means located above said bath whereby, upon yarn breakage, the running yarn end may be led from the feeding means to the storage means around an idle element and the latter may be moved into guiding position while the former guiding element is moved to an idle position.

2. In continuous spinning apparatus including a liquid bath, means for feeding simultaneously a plurality of yarns from said bath, and means for withdrawing simultaneously a plurality of yarns from said bath, the improvement that comprises a pair of spaced yarn guiding elements, means supporting said elements for successive movement into a position for guiding a plurality of yarns within the bath and an idle position above the bath, and a driven storage roller located above the bath whereby, upon yarn breakage, the running end of the yarn may be led from the feeding means to the storage roller around the element in position above said bath, whereupon the means supporting said elements may be actuated to move the elements into mutually substitutive positions.

3. In continuous spinning apparatus including a liquid bath, means for feeding simultaneously a plurality of yarns to said bath and means for withdrawing simultaneously a plurality of yarns from said bath, the improvement that comprises a pair of spaced freely rotatable rollers, a bell crank supporting one of said rollers on each of its arms, said bell crank being rotatable to move said rollers successively to and from a position guiding a plurality of yarns within the bath and an idle position above the bath, and a driven storage roller located above said bath whereby, upon breakage of yarn, the running end may be led from the feeding means to the storage roller around the freely rotatable roller in idle position, whereupon the bell crank may be rotated to move

4 the freely rotatable rollers into mutually substitutive positions.

4. In continuous spinning apparatus including a liquid bath, means for feeding simultaneously a plurality of yarns to said bath and means for withdrawing simultaneously a plurality of yarns from said bath, the improvement that comprises two spaced pairs of freely rotatable rollers, two bell cranks, each of said bell cranks supporting one pair of rollers with the component rollers of the pair on its opposite arms, each of said bell cranks being rotatable to move its rollers successively to and from a thread guiding position within the bath and an idle position above the bath, and a driven storage roller located above said bath whereby, upon breakage of yarn, the running end may be led from the feeding means to the storage roller around the roller in idle position on one of the bell cranks, whereupon that bell crank may be rotated to move the freely rotatable rollers into mutually substitutive positions and then the same procedure is repeated with the other bell crank.

5. In the continuous spinning of rayon yarn that includes simultaneously delivering successive portions of a plurality of yarns to an after-treatment bath in the form of a warp, simultaneously withdrawing successive portions of said warp from said baths while passing said warp under a guiding element in said bath; the method of threading-up an individual yarn after breakage that includes controlling the broken end of yarn issuing from the point of delivery and leading it under a guiding element disposed outside of said bath to a point of temporary collection outside said bath, and substituting said outside guiding element for said bath guiding element to restore said broken yarn to normal position in said bath while avoiding disturbance of said running warp.

6. In the continuous spinning of rayon yarn that includes simultaneously delivering successive portions of a plurality of yarns to an after-treatment bath in the form of a warp, simultaneously withdrawing successive portions of said warp from said baths while passing said warp under a pair of spaced guiding elements disposed in said bath, the method of threading-up an individual yarn after breakage that comprises leading the broken end of yarn issuing from the point of delivery under a guiding element disposed outside of said bath to a point of temporary collection also outside of said bath, substituting said outside guiding element for the bath guiding element nearer the point of delivery, pulling a loop between said point of temporary collection and said substituted guiding element, passing said loop around another guiding element disposed outside of said bath, substituting said other guiding element for the bath guiding element nearer the point of withdrawal, severing the yarn at the point of temporary collection and leading the running end to the point of withdrawal.
